UNITED STATES PATENT OFFICE.

CHARLES E. BIRD, OF MINNEAPOLIS, MINNESOTA, ASSIGNOR TO JULIUS
ROSHOLT, OF MAYVILLE, NORTH DAKOTA.

GRAIN-SEPARATOR.

SPECIFICATION forming part of Letters Patent No. 626,746, dated June 13, 1899.

Application filed June 6, 1898. Serial No. 682,656. (No model.)

To all whom it may concern:

Be it known that I, CHARLES E. BIRD, a citizen of the United States, residing at Minneapolis, in the county of Hennepin and State of Minnesota, have invented certain new and useful Improvements in Grain-Separators; and I do hereby declare the following to be a full, clear, and exact description of the invention, such as will enable others skilled in the art to which it appertains to make and use the same.

My invention relates to grain-separators of the type in which vibrating sieves are employed; and it has for its object to improve the construction of such machines in points hereinafter noted.

The invention consists of the novel devices and combinations of devices hereinafter described, and defined in the claims.

The invention is illustrated in the accompanying drawings, wherein like characters indicate like parts throughout the several views.

Figure 1 is a right-side elevation of the machine. Fig. 2 is a vertical longitudinal section taken centrally through the machine. Fig. 3 is a plan view of a portion of one of the sieves. Fig. 4 is a bottom plan view of the adjustable bottom section of the hopper, which in this construction serves the function of a feed-gate; and Fig. 5 is a vertical longitudinal section of the upper or primary vibrating shoe removed from the machine and provided with sieves which vary in construction and arrangement from those shown in Fig. 2.

Referring in detail to the construction illustrated in Figs. 1 to 4, inclusive, *a* indicates the side brackets, and *a'* the transverse timbers, of the framework of the machine. Rigidly secured to the upper ends of vertical beams of the side frames or brackets *a* is a hopper *b*. This hopper *b* is provided with an adjustable bottom section *b'*, which constitutes or serves as the feed-gate and, as shown, works in grooves *b*², cut in the sides of said hopper. The adjustment of this gate or bottom section *b'* is accomplished by means of a pair of small levers *b*³, that are pivoted to the said section *b'* at *b*⁴ and the outer ends of which work in recesses or notches of fulcrum-blocks *b*⁵, rigidly secured one to each side of the hopper below said section *b'*. The

free ends of these levers *b*³ terminate in close proximity to each other, so that they may be readily engaged with one hand and simultaneously operated, and thereby cause equal movements of both ends or sides of the gate-section *b'*.

Directly below the hopper just described is mounted the primary and uppermost vibrating sieve-shoe *c*, composed principally of side plates, a transversely-extended trough *c'*, and suitable transverse connections. At its forward end the shoe *c* is suspended by short links *c*², the upper ends of which are, as shown, pivoted to the sides of the hopper *b* and the lower ends of which are likewise pivoted to the sides of said shoe. The lower ends of said links *c*² may, however, be adjustably secured in any one of a series of holes *c*³ by removing the bolt or pin which secures the same, so as to vary the rise and fall of that end of the shoe. Rigidly secured to a cross rod or beam *c*⁴ of the shoe *c* is an inclined deflector-plate *c*⁵, which co-operates with the opening in the bottom of the hopper in the feed action. Below the deflector-plate *c*⁵ is an inclined and imperforate feed board or deck *c*⁶, rigidly secured to transverse bars *c*⁷ and *c*⁸ of the shoe *c*. Immediately over the deck *c*⁶ is a screen 1, which, as shown, is removably held in place by a spring *c*⁹.

*c*¹⁰ indicates a flexible sheet or flap which overlies the screen 1 and is secured at its upper end to the cross-bar *c*⁴. The shoe *c* also carries a pair of approximately parallel screens 2 and 3, that are suitably supported thereby and slant reversely from the sieve 1.

*c*¹¹ indicates a flexible sheet or flap which overlies the sieve 2 and is secured at its upper end to the transverse bar *c*⁷.

*c*¹² indicates the inclined deck, which is carried by the shoe *c* and underlies the sieve 3. The shoe *c* also carries a pair of small transversely-extended and reversely-acting deflectors *c*¹³ and *c*¹⁴, the particular relation and action of which will be hereinafter noted.

Below the primary sieve-shoe *c* the secondary sieve-shoe is mounted to vibrate. This secondary shoe *f* is much longer than the primary shoe *c* and projects farther toward the rear of the machine. This shoe *f* is made up principally of side pieces connected at their

ends by transverse troughs or spouts $f' f^2 f^3$ f^4 and longitudinally-extended but reversely-inclined discharge-spouts $f^5 f^6$. The said side plates of the shoe f are shown as further 5 connected at their intermediate portions by a pair of parallel transversely-extended angle-bars or sieve-supports f^7 and f^8 . Imperforate inclined decks f^9 and f^{10} extend, respectively, from the sieve-supports $f^7 f^8$ to the longitudinally-extended discharge-spouts $f^5 f^6$. Extending substantially parallel to the deck f^9 and immediately over the same is a pair of sieves or screens 10 4 5, that lead, respectively, to the troughs $f' f^2$ and are supported at their upper ends by the transverse sieve-support f^7 .

f^{11} indicates the flexible sheet or flap which rests upon the sieve 4 and is secured at its upper end to a transverse bar f^{12} .

Extending substantially parallel to each 20 other and to the deck 10 is a pair of sieves or screens 7 and 8, that lead, respectively, to the transverse spouts or troughs $f^3 f^4$ and are supported at their upper ends by the transverse sieve-support f^8 . The sieves 7 and 8 are, for 25 a purpose hereinafter to be specifically noted, placed very close together. To secure the best results, they should be located approximately one-half inch apart.

The opening between the transverse sieve-supports $f^7 f^8$ is spanned by a screen 6 of such fine mesh that no ordinary material or grain can pass therethrough, but serving to freely pass air from a fan located below the same and to be presently described. Secured to 30 the sides of the secondary shoe f and extending above the sieves 7 and 8 transversely of the machine is a discharge-spout f^{13} , that is open at its forward edge. The deflector c^{14} projects into this spout f^{13} and, together with 35 the deflector c^{13} , serves to deflect or guide certain of the particles of the grain or stock into said spout f^{13} . Immediately below the deflector c^{14} is a pivoted segmental deflector or throat-controlling gate f^{14} , the pivot-shaft of 40 which is mounted in the sides of the shoe f and provided at one projecting end with a spring-arm f^{15} , that co-operates with a latch-segment f^{16} on one of the sides of said shoe f .

The rear ends of the side plates of the shoe 50 f are provided with small wheels or antifriction-rollers f^{17} , that work on the upper face of a transversely-extended support f^{18} . This support f^{18} extends between the frame-brackets a and is adapted for pivotal adjustment 55 on a longitudinal axis around a clamping-rod f^{19} . By tightening the bolt f^{19} the support f^{18} may be securely clamped and held in any set position, and by increasing the incline of the upper face of said support f^{18} the amount of 60 rise and fall or vertical movement which that end of the secondary shoe will receive when vibrated, as presently described, may be increased at will.

The forward ends of the primary shoe c and 65 secondary shoe f are supported by a pair of vibrating levers g , pivoted to the said shoes by means of brackets g' and g^2 , respectively.

Intermediate of the brackets $g' g^2$ the levers g are provided with offset lugs or projections g^3 , which are pivoted to fulcrum brackets 70 or blocks g^4 , fixed on transverse portions a^2 of the main frame of the machine. This offset fulcrum will give an increased vertical movement to the forward ends of the shoe under the vibrating actions of the levers. 75

The fan, which, as heretofore indicated, is located below the very fine sieve 6, may be of any approved form; but as preferred it consists of the fan-case k , the neck k' of which is positioned to discharge directly through 80 the fine sieve 6, and the fan-blades k^2 , carried by the shaft k^3 and operating in the ordinary manner. The throat or passage through the neck k' is adapted to be opened and closed to a greater or less extent by means of a gate-valve k^4 , the shaft of which projects through one side of the fan-case k and is provided with a spring-arm k^5 , that co-operates with a latch-segment k^6 to hold said valve k^4 whenever set. 85

The fan-shaft k^3 projects and is provided at its ends with cranks k^7 , which are connected to the depending ends of the supporting-levers g by means of pitmen n . These pitmen n are connected to the depending ends of said 90 levers by the bolts or pins n' , which are adapted to be inserted into any of the series of holes n^2 in said levers to thereby vary the strokes which said levers, and consequently said sieve-shoes, will be given under the 95 crank motions of the cranks k^7 . One projecting crank end of the shaft k^3 is also provided with a small sprocket-wheel p . A relatively very large sprocket-wheel p' is mounted on a stud p^2 , secured to and projecting from one 100 side of the main frame a . A sprocket-chain p^3 runs over the sprocket-wheels p and p' . The sprocket-wheel p' is provided with a hand-crank p^4 , which adapts the machine to be run by hand. If desired to run the 105 machine by power, either the sprocket-wheel p' or fan-shaft k^3 might be provided with a pulley, or other suitable driving connections might be provided. 110

The construction illustrated in Fig. 5 is 115 similar to that illustrated in Fig. 2, with the following exceptions: Sieves 9 and 10 are substituted for sieve 1 of the above-described construction, and sieves 11, 12, 13, and 14 are substituted for sieves 2 and 3. It will be 120 noted that the sieves 9 and 10 are placed in staggered relation with respect to each other, and likewise that sieves 11 and 12 and 13 and 14 are staggered or offset with respect to each other or set in different vertical planes. 125

To better illustrate the relation which the various sieves so far described bear to each other, the following dimensions of the meshes of the same are given; but it will of course be understood that these dimensions may be varied. As preliminary to this it may, however, be timely stated that the arrangement provided for in the machine illustrated in Figs. 1 to 4, inclusive, is especially adapted and 130

designed for the separation of rice from the foreign matter or refuse with which it is usually mixed: Sieve 1 has one-fourth inch round perforations, sieve 2 has thirteen sixty-fourths round perforations, sieve 3 has twelve sixty-fourths round perforations, sieve 4 has ten sixty-fourths round perforations, sieve 5 has seven sixty-fourths round perforations, sieve 6 is extremely fine and is preferably of woven wire, sieve 7 has thirteen sixty-fourths round perforations, and sieve 8 has meshes which are elongated and run about thirteen to the inch in one direction and two to the inch in the other direction.

15 The arrangement of sieves illustrated in Fig. 5 is especially adapted for the separation of wheat and oats. This mixture is grown in large quantities in many localities where the conditions of the soil demand such a mixture 20 and is commonly designated as "succotash." The sieve-section 9 has thirteen sixty-fourths inch round perforations, the sieve-section 10 has twelve sixty-fourths round perforations, the section 11 has twelve sixty-fourths round 25 perforations, section 12 has seven sixty-fourths round perforations, section 13 has twelve sixty-fourths round perforations, and section 14 has six sixty-fourths round perforations. However, as previously stated, these 30 exact dimensions are simply given to illustrate the relation of the sieves, and hence I do not limit myself to such dimensions.

As shown, flexible flaps or sheets c^{15} , c^{16} , c^{17} , and c^{18} work over the tops of the sieve-sections 9, 10, 11, and 12, respectively. The lower end of the sieve-section 12 cooperates with the extended imperforate section c^{19} , which when said shoe is placed in working position or substituted for the shoe c , employed in Fig. 2, 40 overlaps the deflector or imperforate deflector f^{14} .

Operation: The operation of the construction illustrated in Figs. 1 to 4, inclusive, will be substantially as follows: As is well known, 45 rice is usually mixed with a growth known as "tadpole," with various foul seeds, and more or less chaff and dirt. Tadpole is a peculiar seed consisting of a pod with a short stem, making the seed usually from five-eighths to three-fourths of an inch long. On account of 50 its peculiar form it is very difficult to remove the tadpole from the rice. With these statements in mind the operation will be better understood. The rice and foreign mixtures are 55 placed in the hopper b and fed through the opening b^2 , which opening may be varied, as previously described. When the shoe c is at rest, the flow of a small amount of grain will clog the passage b^2 and stop the flow for the 60 time being; but when the shoe is vibrated the deflector-plate c^5 , vibrating back and forth, will pass through the stream of grain which is attempting to flow through the passage b^2 and will cause a forced feed of the grain onto 65 the sieve or screen 1. All of the stock or material will pass through the coarse sieve 1, except chaff, straw, or other large material,

which will be discharged into the transverse trough c' and from thence to any suitable point of discharge. The material which passes the 70 sieve 1 will be directed by the deck c^6 onto the sieve 2. All of the stock except No. 1 rice and the tadpoles will pass through both sieves 2 and 3 and will be directed onto the sieve 4 by the deck c^{12} . More or less of the No. 1 rice 75 may pass through the sieve 2, but will not pass through the sieve 3, and hence this No. 1 rice, mixed with tadpoles, will be passed over the fine sieve 6. In passing over this sieve 6 the rice and tadpoles will be passed 80 through the blast from the fan k^2 , and the tadpoles being much lighter than the rice more or less of the same will be blown into the spout f^{13} , while the rice and the remainder of the tadpoles, with which it is mixed, will pass onto 85 the sieve 7. Now the head of the tadpole will pass through a perforation of such diameter that it will not pass either No. 1 or No. 2 rice. The perforations in the sieves 7 are of such 90 diameter that they will not pass No. 1 rice, but will pass No. 2 rice and the tadpoles. No. 1 rice will thus be discharged into the transverse trough f^8 . The elongated meshes of the sieve 8 are so narrow that they will not 95 pass the No. 2 rice, but will pass the tadpoles. Hence the No. 2 rice will be discharged into the transverse trough f^4 , while the remainder of the tadpoles will be discharged through the spout f^6 .

As the sieves 7 and 8 are located a less distance apart than the length of a tadpole, it is evident that the tadpoles will be presented endwise to the sieve 8, thus making their passage through the meshes of said sieve 8 much more certain than if presented in any other 105 way. This relative arrangement of the sieves is very important.

We have now followed out the successive steps by which the tadpoles are separated from the No. 1 and No. 2 rice. By opening or 110 closing the gate-valve k^4 of the fan the intensity of the blast of air on the material passing over the sieve 6 may be regulated so as to give the best results under different conditions. By adjusting the segmental deflector f^{14} the throat-opening to the spout f^{13} may 115 be varied. Any rice which might possibly be blown slightly above this sieve 6 would on account of its weight in excess of the tadpoles fall upon the deflector f^{14} and be thereby caused to roll back onto said sieve 6. By the proper manipulation of the valve k^4 and deflector f^{14} it is possible to remove all light 120 dirt and dust and a great many of the tadpoles from the rice in its passage over the sieve. 125 6 without causing a waste of the good rice.

It will be remembered that only the rice and tadpoles, together with some dirt or dust and possibly some light chaff, were delivered 130 to the sieve 6. Such substances as hulled rice, broken rice, red rice, and small foul seeds were passed through the sieve 3 and delivered onto the sieve 4. This sieve 4 will pass the broken rice and small round seeds,

- but will deliver the hulled rice and red rice (which latter is smaller than the white rice) to the transverse spout f^1 . The sieve 5 will deliver the broken rice into the transverse spout f^2 , but will pass the small foul seeds or other small material, which material will be discharged from the spout f^5 . The flexible flaps or sheets c^{10} , c^{11} , and f^{11} , for example, operate in the ordinary manner to hold the grain flat and prevent it from jumping too high on the sieves with which they coöperate. However, in the construction illustrated in Fig. 5 the flexible flaps c^{16} and c^{18} serve additional functions—to wit, that of imperforate conveyers for delivering the material not passed through the sieves 9 and 11, respectively, over and above the sieves 10 and 12, respectively. This latter arrangement is thought to be novel.
- Attention is now particularly called to the fact that the primary sieve 1, which is of very coarse mesh, serves to separate and carry off all of the coarse chaff before the stock is passed through the blast of the fan. This greatly reduces the amount of work which would otherwise be thrown upon the blast.
- When the construction or arrangement of sieves illustrated in Fig. 5 is substituted in the shoe c and the machine is used to separate wheat and oats, I would preferably also substitute for the sieve 7 a sieve of the same construction as sieve 8, (see Fig. 3,) but of slightly-coarser mesh, so that it would pass oats, but not wheat.
- It will of course be understood that I do not limit myself to the specific details of construction above set forth, but, on the contrary, that

my invention is capable of alterations other than those noted.

What I claim, and desire to secure by Letters Patent of the United States, is as follows:

1. In a grain-separator, the combination with a shaking shoe, of a pair of overlapping sieves of unequal length, and a flexible flap mounted to serve as a tailings extension for the upper or shorter sieve, and as a rider for the lower sieve, substantially as and for the purposes set forth.

2. In a grain-separator, the combination with an upper shaking shoe c having separating-sieves, of a lower shoe f having separating-sieves, the intermediate sieve 6 receiving the overtail from the upper and delivering the same to the lower separating-sieves, a blast-fan having its delivery-spout k' directly undersaid sieve 6, a regulating-valve k^4 in said blast-spout, the discharge-spout f^{13} receiving the material blown from the sieve 6 and the regulating-valve f^{14} in said discharge-spout, all for coöperation substantially as described.

3. In a feed-hopper, the combination with the fixed sides b of the endwise-movable bottom b' , and the levers b^3 pivoted to said bottom intermediate of their extremities, as at b^4 , and having their outer ends fulcrumed to fixed parts of the hopper with their free ends extending near to each other for joint operation with one hand, substantially as described.

In testimony whereof I affix my signature in presence of two witnesses.

CHARLES E. BIRD.
